UNITED STATES PATENT OFFICE.

FREDERICK W. WAKEFIELD, OF VERMILION, OHIO, ASSIGNOR TO THE F. W. WAKEFIELD BRASS COMPANY.

DOUBLE-LOCKING HOLDER FOR LIGHTING FIXTURES.

Application filed February 17, 1922. Serial No. 537,281.

To all whom it may concern:

Be it known that I, FREDERICK W. WAKEFIELD, a citizen of the United States, and a resident of Vermilion, county of Erie, and 5 State of Ohio, have invented a new and useful Improvement in Double-Locking Holder for Lighting Fixtures, of which the following is a specification, the principle of the invention being herein explained and 10 the best mode in which I have contemplated applying that principle so as to distinguish it from other inventions.

The present invention relates to a lighting fixture in which the holder for a globe 15 is provided with means for engagement with the globe itself without the use of screws, and added provision is also made for positively locking the holding means in place when the fixture is assembled. To the accomplishment of the foregoing and related 20 ends, said invention, then, consists of the means hereinafter fully described and particularly pointed out in the claims.

The annexed drawing and the following 25 description set forth in detail certain mechanism embodying the invention, such disclosed means constituting, however, but one of various mechanical forms in which the principle of the invention may be used.

30 In said annexed drawing:—

Fig. 1 is a vertical sectional view through the globe holder; Fig. 2 is an enlarged sectional view showing the globe locked in place; Fig. 3 is a sectional view on the line 3—3 of Fig. 1; Fig. 4 is a perspective view of one of the spring fingers; and Fig. 35 5 is a sectional view of a portion of the holder with the canopy removed, showing the parts in releasing position in dotted lines.

40 As shown in the drawings the fixture consists of the usual lower canopy 5, with a supporting chain 2 having a ceiling support (not shown) at the other end. The chain is secured to an inverted cup 6 or holder, the cup having a central aperture 7 in which is mounted a hollow boss 8, having a chain link 9 attached thereto, the supporting chain 2 being secured to this link 9. The 45 hollow boss is adapted to receive the wires to allow them to reach the lamp socket 10, which is supported in place on the under side of the cup by means of two straps 11, which are secured to the cup by means of 50 screws 21 or the like.

The globe holding means comprise three spring fingers 30 having angled ends 31 apertured to receive the screws 32 by which they are secured to the cup and the lower ends of the fingers have rectangular bends 60 to form the receiving ends for the globe. The fingers extend from the cup outwardly and downwardly and just above the horizontal portion 32 are provided with tangs 33 punched up from the fingers. 65

A holder disk 34 is employed which is merely a flat plate with one side 35 cut away to form a hand opening. This disk or plate is provided with two narrow slots 36 and one wider slot 37 and the fingers are 70 threaded through these slots so that the plate is normally supported by the fingers and is prevented from rising by the three tangs 33. The wide slot 37 is adjacent the cut away portion 35 and the slot is wide 75 enough to allow the finger to be pressed inwardly sufficiently for the tang to pass through the slot allowing the plate to rise into the position shown in dotted lines in Fig. 5 and this releases the finger which 80 assumes the position shown in dotted lines in Fig. 5 to allow the globe to be removed.

When the globe is to be inserted it is placed in the fingers in the slots 36 and the plate or disk is lowered to engage the 85 third finger and when thus engaged the plate is below and in engagement with the tang so that the globe is locked in place.

The usual type of canopy 5 is employed which fits over the holding cup and rests 90 thereupon, and the canopy is adapted to fit snugly against the periphery of the holder disk to positively prevent upward movement of the holder relative to the spring arms so that when the canopy is in place, the position of the spring arms in the disk holder 95 is positively secured and the globe cannot be removed from the arms until the canopy has first been raised.

In the present lighting fixture, there has 100 been secured locking means for the globe without the use of screws and the globe is doubly locked in place when the fixture is completely assembled and the canopy positioned. When the canopy is raised, the 105 upper edge of the globe may be grasped by the operator and then by pressing inwardly the disk holder finger in the wide slot may be sprung upwardly over the tang in the third finger and the globe will be released 110

due to the spring action of the fingers. When it is desired to insert the globe, it is placed in position in the two semi-rigid fingers and the disk holder is then forced down to lock the third finger over the lip of the globe and the holder will then carry the globe without danger of releasing the same, and as soon as the canopy has been lowered into position, the spring fingers and the disk holder are positively locked in their engaging position so that the holder cannot be accidentally lifted to release the fingers.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a lighting fixture and globe holder, the combination of a cup provided with a socket and attaching means, resilient fingers attached to said cup and provided with ends adapted for engagement with a globe, a slotted disk mounted on said fingers and adapted in one position to lock said fingers in globe engaging position, and a canopy adapted to fit over said cup fingers and to lock said disk against upward movement to prevent accidental release of said fingers when said canopy is in position.

2. In a lighting fixture and globe holder, the combination of a cup provided with a socket, a plurality of downwardly and outwardly extending spring fingers attached at their upper ends to said cup, said fingers

having their lower ends adapted for engagement with the lip of a globe, said fingers being normally spread apart to receive a globe, and a holder disk having slots to receive said fingers, two of such slots snugly receiving said fingers, the other such slot being wider, said first fingers having means to retain the same in engagement with the edges of such respective slots, such third finger having means for detachably engaging such wider slot to permit the displacement of said fingers from its globe engaging position.

3. In a lighting fixture and globe holder, the combination of a cup provided with a socket, a plurality of downwardly and outwardly extending spring fingers attached at their upper ends to said cup, said fingers having their lower ends adapted for engagement with the lip of a globe, said fingers being normally spread apart to receive a globe, a holder disk having slots to receive said fingers, two of such slots snugly receiving said fingers, the other such slot being wider, said first fingers having means to retain the same in engagement with the edges of such respective slots, such third finger having means for detachably engaging such wider slot to permit the displacement of said fingers from its globe engaging position, and a canopy adapted to fit over and enclose said fingers and holder and adapted to prevent upward movement of said holder disk.

Signed by me, this 11th day of February, 1922.

FREDERICK W. WAKEFIELD.
